UNITED STATES PATENT OFFICE.

HARRY L. TOOKER, OF TAUNTON, MASSACHUSETTS, ASSIGNOR TO TAUNTON PEARL WORKS, INCORPORATED, OF TAUNTON, MASSACHUSETTS, A CORPORATION OF MAINE.

BELT BUCKLE.

Application filed February 1, 1922. Serial No. 533,294.

To all whom it may concern:

Be it known that I, HARRY L. TOOKER, a citizen of the United States, residing at Taunton, in the county of Bristol and State 5 of Massachusetts, have invented certain new and useful Improvements in Belt Buckles, of which the following is a specification.

This invention relates to new and useful improvements in the construction of belt 10 buckles, and the object of this invention is to provide a buckle of this character in which one end of a belt is secured to one member of the buckle and the opposite end is secured to another member of the buckle and the two 15 buckle members are adapted to be detachably connected together so that the belt may be removed without interfering with its adjusted length.

With these and other objects in view, the 20 invention consists of certain novel features of construction, as will be more fully described, and particularly pointed out in the appended claims.

In the accompanying drawings,

25 Figure 1 is a front view of my improved buckle showing the opposite ends of the belt as being secured to different members thereof.

Figure 2 is a rear view of my improved 30 buckle showing the back plate as provided with openings to receive the locking studs in the removable or detachable member which latter is indicated in dotted lines in its first position upon being applied to the back plate 35 and before being rotated into working position.

Figure 3 is an end view showing the clamp by which one end of the belt may be adjustably secured in the buckle body.

40 Figure 4 is a rear view sectioned to show the edge flanges of the front and back members as being one within the other and secured together.

Figure 5 is a perspective view showing the 45 back plate removed from the front plate member.

Figure 6 is a perspective view showing the detachable member on the face of which is carried the pivot pin and the two locking 50 studs which are adapted to enter the openings in the back plate of the body.

Figure 7 is a detail view of the clamping member.

With reference to the drawings, 10 designates the body portion of my improved

buckle which is provided with rearwardly extending edge flanges 11, which flanges are provided near one end of the body with extensions which are folded inwardly to form pivot ears 12 in which a clamping member 13 is pivoted on its trunnions 14 and is for the purpose of clamping and adjustably securing one end 15 of the belt to the body portion.

The back plate member 16 of this buckle 65 is also preferably provided with side flanges 17 which are adapted to fit closely inside of the flanges 11 of the front plate and at one end these flanges 17 are provided with short extensions 18 adapted to fit under the 70 inturned pivot ears 12 and the flanges at the opposite ends of this member are notched as at 19 which notches are engaged by in-turned tongues 20 thereby firmly locking and securing the back plate to the front plate 75 through the locking of their respective flanges 11 and 17 together.

The face of this back plate 16 is provided with slots or openings 21, each cut on the arc of a circle, one end of each slot being 80 enlarged as at 22 to receive the head of the locking studs while the opposite ends of these slots are offset laterally as at 23 providing recesses into which the necks of these studs are drawn to lock the parts together 85 from moving toward unlocked position while tension is on the belt. These slots 21 are formed on opposite sides of the pivotal opening 24.

In order to provide a readily detachable 90 member or one which may be easily removed from the body of the buckle without destroying the adjustably clamped end of the belt, I have provided such a member, preferably in the form of a plate 25, one end of which 95 is enlarged as at 26 and is cut away as at 27 providing a bail in which the opposite end 28 of the belt may be permanently secured and to the inner face of this detachable member I have secured a pivot pin 29 which 100 is adapted to enter the central pivot opening 24 in the back plate, and I have also provided a pair of locking studs 30, each having an enlarged head which is adapted to enter the enlarged openings 22 at the entering ends of the slots whereby this plate after 105 having been positioned, as illustrated by dotted lines in Figure 2, on the back plate of the buckle member, may be rotated on its pivot pin and swung down into alignment 110

with the buckle body and when tension is applied to the belt, the necks of the locking studs will be moved laterally or toward the end of the back plate to engage the offset 5 openings 23 in the slots 21, which movement is permitted by the elongated central pivot opening, and when these studs are in this adjusted position the buckle parts cannot be accidentally disconnected so long as there 10 is tension upon the belt.

When it is desired to disconnect the buckle parts it is only necessary to press the detachable member and the buckle body end-ways towards each other which releases the 15 studs from these recesses 23, when by rotating or lifting the bail end of the member the studs will be rotated into position to be readily removed through the enlarged openings 22.

20 It will be seen by this construction that the weight of the front portion of the belt which causes the buckle and belt ends to sag, automatically serves to hold the buckle parts in locked position even though the belt were 25 very loose about the body of the wearer.

It is found in practice in swinging the top plate back into release position, as shown in dotted lines in Figure 2, that oftentimes the heads of the studs 30 will catch under 30 the adjacent edges of the plate thus preventing the free removability of member 25 from the body of the buckle. To obviate this difficulty I have bent down a portion of the stock around the outer edge of these 35 openings forming downwardly extending flanges 31 against which the head portions of the studs engage and which serve to guide the studs out through the openings as the plate is removed from the body of the buckle.

40 My improved buckle is very simple and practical in construction and by its use the parts may be readily disconnected from each other to release the belt without disturbing its adjusted length and the parts of the buckle may be readily connected together by simply placing the detachable member upon the back plate of the buckle and rotating the same about 30°.

45 The foregoing description is directed solely towards the construction illustrated, but I desire it to be understood that I reserve the privilege of resorting to all the mechanical changes to which the device is 55 susceptible, the invention being defined and limited only by the terms of the appended claims.

I claim:

1. A belt buckle comprising a body member having spaced apart front and back plates, means for securing one end of the belt between said plates, said back plates being provided with a laterally-extending lock stud receiving opening enlarged at its 65 outer end and extending longitudinally of

the buckle at its inner end, a detachable member to which the opposite end of the belt is adapted to be secured, said member having a locking stud adapted to engage the opening in said back plate and be moved both laterally and longitudinally to locked position therein. 70

2. A belt buckle comprising a body member having spaced apart front and back plates, means for securing one end of the belt between said plates, said back plate being provided with lock stud receiving openings, a detachable member to which the opposite end of the belt is adapted to be secured, said member having a pivot pin and a locking stud with an enlarged head adapted to engage the openings in said back plate and be moved to locked position therein by a relative rotary motion and prevented from moving from locked position by tension on the belt parts. 80

3. A belt buckle comprising a body member having spaced apart front and back plates, means for securing one end of a belt between said plates, said back plate being provided with a central pivot hole and a pair of oppositely disposed arc-shaped openings, and a detachable member to which the opposite end of the belt is adapted to be secured having a pivot pin and a pair of locking studs having enlargements adapted to enter and be moved in a circular direction into unlocked position therein to releasably secure said member to said body. 90

4. A belt buckle comprising a body member having a front member spaced from a back plate, means for adjustably securing one end of a belt between said member and plate, and a detachable plate to which the opposite end of the belt is adapted to be secured, one of said plates having a central pivot hole and a pair of oppositely-disposed arc-shaped openings and the other having a pivot pin and a pair of locking studs with enlargements adapted to enter the openings in the other plate, said plates being adapted to receive a relative circular movement to releasably lock them together. 100

5. A belt buckle comprising a hollow body having a front plate and a back engaging member, means in said body for adjustably securing one end of a belt between said member and plate, a detachable member to which the opposite end of the belt is connected, a lock stud in one of said members and a complementary slot in the other of said members adapted to receive said stud whereby when the stud is positioned in its slot the two may be firmly locked together by a relative rotary motion of said members, and means for guiding said stud from engaging position. 115

6. A belt buckle comprising a hollow body having a front member with side flanges, a separate back plate connected to said flanges, 120

means in said body for adjustably securing one end of a belt between said member and plate, a detachable plate to which the opposite end of the belt is connected, a lock stud in one of said plates, and a complementary key hole slot offset at its smaller end in the other of said plates adapted to re-

ceive said stud whereby when the stud is positioned in its slot the two plates may be firmly locked together by a relative rotary 10 and endways motion of said plates.

In testimony whereof I affix my signature.

HARRY L. TOOKER.
